C. Snow & Co.

UNITED STATES PATENT OFFICE.

JOHN WINKELMANN, OF MILWAUKEE, WISCONSIN.

PENDULUM LEVEL AND PLUMB.

SPECIFICATION forming part of Letters Patent No. 469,430, dated February 23, 1892.

Application filed March 4, 1891. Serial No. 383,740. (No model.)

To all whom it may concern:

Be it known that I, JOHN WINKELMANN, a citizen of the United States, residing at Milwaukee, in the county of Milwaukee and State 5 of Wisconsin, have invented a new and useful Level, of which the following is a specification.

This invention relates to that class of levels which are provided with weighted pendulums 10 adapted to indicate automatically and by the force of gravity the deflection from the level or plumb; and it has for its object to provide a device of this class which shall possess superior advantages in point of simplicity, durability, and general efficiency.

With these ends in view the invention consists in the improved construction, arrangement, and combination of parts, which will be hereinafter fully described, and particularly pointed out in the claims.

In the drawings hereto annexed, Figure 1 is a perspective view of a level constructed in accordance with my invention. Fig. 2 is a part sectional side elevation of the device with 25 one side removed to expose the interior construction. Fig. 3 is a transverse sectional view taken on the line 3 3 in Fig. 2. Fig. 4 is a transverse sectional view taken on the line 4 4 in Fig. 2.

Like numerals of reference indicate like parts in all the figures.

1 designates a suitable box or casing, which is provided with interior transversely arranged pins 2 and 3, both of which are provided with knife-edges, in order to afford bearings for the levers or pendulums 4 and 5, the former of which is arranged longitudinally and the latter transversely in the casing. The said pins are provided with screw-threaded ends, by means of which they are mounted in one side of the casing, the opposite ends being pointed, as shown at 6, to engage the opposite side of the casing. The screw-threaded ends of the said pins are provided with 45 transverse notches 7, which may be readily engaged by a screw-driver for the purpose of adjusting the said pins when necessary to the proper position, and the screw-threaded ends of said pins are normally covered by means 50 of a plate 8, secured to the side of the casing by means of a screw 9, in order to prevent the

said pins from being accidentally displaced. The lower ends of the pendulums 4 and 5 are provided with weights 10 of suitable size and shape to cause the said pendulums to assume 55 normally a vertical position. The upper ends of the said pendulums are bifurcated, as shown at 12.

The interior of the box or casing is provided with guide-strips 13 of metal, arranged 60 transversely to the pendulums near the lower ends of the latter, in order to avoid undue friction of said pendulums against the sides of the casing. A staple, as shown at 14, may also be arranged transversely across the longer 65 pendulum 4, in order to prevent the same from rattling in the casing.

The box or casing is provided near its upper end with a transverse strip or indicator 15, suitably secured and which is straddled by 70 the bifurcated upper end of the pendulum 4. The indicating-strip 15 is provided with marks 75 16 to indicate the plumb and various degrees of deflection from the same. The said indicating-strip, as well as the upper end of the pendulum 4, is visible through glasses 17, that cover openings 18 in both sides of the casing. The said glasses may be secured in position by means of exterior rings 19, of brass or other suitable material.

One edge of the casing is provided with a metallic box 20, having slots or openings 21, into which the bifurcated end of the pendulum 5 is extended. Transversely across the said slots are formed marks 22 to indicate the 85 level and various degrees of deflection therefrom. A pivoted or sliding cover 23 is provided to normally cover the slots or openings 21 and to prevent foreign matter from entering the casing.

The edge of the casing opposite to that having the box 20 is provided with transverse metallic strips 24, mounted in dovetailed grooves 25 and serving as wear-plates to enable the level to be used for brick-laying and 95 similar rough work without danger of being injured in such a manner as to interfere with its accuracy.

The operation of this invention will be readily understood by those skilled in the art to 100 which it pertains from the foregoing description, taken in connection with the drawings

hereto annexed. The construction is exceedingly simple and inexpensive and the apparatus is certain in its operation, as well as very accurate. The pivotal pins upon which the 5 levers or pendulums are mounted are provided with knife-edges, as described, thus rendering the said pendulums exceedingly sensitive. If by any accident the said pins should become displaced, they may be readily restored by the use of an ordinary screw-driver, the covering-plate being meanwhile removed to render their notched ends accessible.

Having thus described my invention, I claim and desire to secure by Letters Patent of the 15 United States—

1. In a level of the class described, the combination of the casing, the knife-edged pivotal pins having screw-threaded ends mounted in one side of the casing and provided with transverse notches, and the levers or pendulums mounted upon said pins, substantially as and for the purpose set forth. 55

2. In a level of the class described, the combination of a box or casing, the knife-edged pins having pointed ends engaging one side of the casing, and screw-threaded and transversely-notched ends mounted in the opposite side of said casing, and the levers or pendulums mounted upon said pins, substantially as and for the purpose set forth. 60

3. In a level of the class described, the combination of the knife-edged pins having screw-threaded and transversely-notched ends mounted in one side of the casing, the covering-plate mounted detachably over the notched ends of said pins, and the levers or pendulums mounted upon the latter, substantially as and for the purpose set forth. 65

4. In a level of the class described, the combination of the box or casing, the transverse strip or indicator arranged near the upper end of the same and having suitable marks, the lever having a bifurcated end straddling

said strip, and the sight-glasses in opposite sides of the casing, substantially as and for the purpose set forth. 70

5. In a level of the class herein described, the combination of the box or casing, the knife-edged pins, the levers or pendulums mounted upon the latter, and the guide-strips arranged in the said casing transversely to the levers or pendulums, substantially as and for the purpose set forth. 75

6. In a level of the class herein described, the combination, with the box or casing and the knife-edged pivotal pins mounted adjustably in the side of said casing, of the levers or pendulums having bifurcated ends, a transverse strip or indicator arranged between the sight-glasses at the upper end of the casing for the bifurcated end of one pendulum, and the box mounted upon one edge of the casing and having slots to receive the bifurcated end of the other pendulum, substantially as and for the purpose set forth. 80

7. In a level of the class described, the combination, with the box or casing, of a transversely-arranged lever or pendulum having a bifurcated upper end, the box attached to one edge of the casing and having slots to receive the bifurcated end of said pendulum, and a slide or cover pivoted upon the said box, substantially as and for the purpose set forth. 85

8. In a level of the class described, the combination, with the box or casing having the levers or pendulums, of the strips or wear-plates mounted in dovetailed grooves in one edge of the said casing, substantially as and for the purpose set forth. 90

In testimony that I claim the foregoing as my own I have hereto affixed my signature in presence of two witnesses.

JOHN WINKELMANN.
